DAYLIGHT LOADING DEVICE FOR DEVELOPER TANKS

Paul Hagen, deceased, late of Brooklyn, N. Y., by
 Margaret Hagen, Brooklyn, N. Y., administratrix

Application April 3, 1937, Serial No. 134,806

9 Claims. (CL. 95—90.5)

This invention relates to new and useful improvements in a developer tank for strips of film and has more particular reference to a daylight loading device therefor.

- 5 This invention relates to the type of developer tank illustrated and described in the co-pending application Serial No. 87,947 filed June 29th, 1936, and entitled "Developer tank for strips of film".
- 10 The invention proposes the provision of a light-proof loading box arranged on the body of a developer tank having a movable film carrier, and an arrangement associated with the loading box for laying a film from a cartridge of film on the carrier.

15 An important feature of the invention is that the film is laid on the carrier and not slid or forced thereon. The reason for engaging the film in this manner upon the carrier is that, even should the developer tank contain some of the developing liquid or be wet, it is possible to lay the film on the carrier. When the film is slid into position on the carrier it may be possible to place it in position if there is total dryness present. But should there be some fluid or moisture present the film will stick to the carrier and it will be virtually impossible to slide it along into proper position. It may be possible to slide or shift the film partially on the carrier, but soon the adhesive quality of the wet film will make itself manifest.

20 Still further the invention proposes to provide a shuttle for the cartridge of film, mounted within the loading box and a means for operating the shuttle to lay the film upon the carrier.

25 The invention further proposes the provision of means for cutting off the inner end of the film from the cartridge after the film has been laid upon the carrier.

30 Another one of the objects of this invention resides in the provision of a passage in the wall of the body between the light-proof leading box and the tank through which the film may be laid upon the carrier, and the provision of a shutter for closing said opening after the film is in position on the carrier.

35 Still further the invention proposes the provision of means operable from the exterior of the device by which the inner end of the film may be secured to the carrier prior to the time it is cut free from the cartridge.

40 Another object of the invention is the construction of a device as described which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a perspective view of a developer tank constructed according to this invention. 10

Fig. 2 is another perspective view viewing the tank from the left hand side.

Fig. 3 is a transverse sectional view taken on the line 3—3 of Fig. 1.

Fig. 4 is a longitudinal sectional view taken on the line 4—4 of Fig. 3. 15

Fig. 5 is a fragmentary transverse sectional view taken on the line 5—5 of Fig. 4.

Fig. 6 is a fragmentary horizontal sectional view taken on the line 6—6 of Fig. 2. 20

Fig. 7 is a fragmentary sectional view taken on the line 7—7 of Fig. 2.

Fig. 8 is a fragmentary perspective view of the front left hand portion of the film carrier shown in Fig. 4. 25

The daylight loading device is used in combination with a developer tank 10 for strips of film having a light-proof body housing a film carrier 11. A light-proof loading box compartment 12 is arranged on one side of the body and 30 adapted to be opened. A shuttle 13 for a cartridge 14 of film 15 is mounted in the compartment 12 and upon the shuttle 13. A catch 16 (see Fig. 4) is mounted on the film carrier 11 and is cooperative with the outer end of the film 15 for holding the end on the carrier. A means is provided for operating the shuttle 13 to lay the film 15 upon the carrier 11, as will hereinafter be more fully described. 35

The developer tank 10 has a cover portion 10a 40 and a body portion 10b adapted to be engaged one with the other to keep out the light. The film carrier 11 comprises a drum 11a upon which there is a helical track 11b. The drum 11a is rotatively supported in the body portion 10 and 45 has a projecting axial shaft 17 upon which a pulley 18 is mounted by which the carrier may be rotated. The details of the carrier, the light-proof construction of the device, and other parts not essential to the complete understanding of the present invention will be omitted as they have been explained in the co-pending application previously identified. 50

The compartment 12 is formed by a box portion built on to the side of the tank. This box 55

portion consists of a bottom box section 10c secured upon the side of the body 10 and cooperative with a covering section 10d removably mounted upon the bottom box portion 10c. There is an opening 19 in the wall of the cover 10a of the tank, within the compartment 12, through which the film may be laid on the carrier. The cover 10d has light-proof flanges 20 secured along its edge and engageable into the top edge of the box portion 10c for providing a light-proof container.

Along the top edge the box cover 10d has an inturned flange portion 10dd (see Fig. 3) cooperative with an upturned flange portion 10aa along the edge portion of the cover 10a to form a light-proof junction. The box cover 10d may be removed for giving access to the shuttle 13 so that a cartridge of film to be developed may be placed on the shuttle.

The shuttle 13 is supported by several guide elements 21 which engage a bar 22 extending longitudinally through the compartment 12. This bar acts as a track for the shuttle to move on. The shuttle 13 has a side arm 13a to support one end of the cartridge 14 and an opposed side arm 13b to support the other end. This latter side arm is adjustably mounted by a screw 23 mounted on a base arm 13c on the shuttle and engaging through a slot 23' in one end of the arm 13b. The screw 23 may be loosened to shift the arm 13b to remove or replace the cartridge of film 14 on the shuttle. The cartridge 14 is supported at an inclination so as to be at right angles to the projected inclination of the helix of the tracks 11b so that the film 15 need not twist in engaging upon the tracks 11b.

The catch 16 may be of any design or construction. As shown, it comprises a hook portion 16a which may be pierced through the end of the film 15 and an elastic band 16b by which the hook portion 16a is attached to the wall of the carrier 11.

A means is provided for operating the shuttle 13 to lay the film 15 on the carrier 11. This means includes a finger 24 which is pivotally supported by a pintle 25 upon the arm 13a of the carrier. This finger may engage through the opening 19 and may engage against one side of the helical track 11b. The rod 22 has reduced end portions 22a and 22b which engage through the end walls of the box body 10c to removably support the bar 22. A nut 26 is mounted upon the end 22a. A radial arm 27 is mounted on the end 22b. A holding screw 28 threadedly engages through the extremity of the arm 27 and is adapted to engage the side wall of the tank body 10b to hold the rod 22 in various turned positions. It is proposed that the screw 28 hold the rod as shown in Fig. 3, in which position the shuttle is ready to lay the film on the carrier. Or it is proposed that the screw 28 be loosened and the radial arm 27 be moved angularly to tilt the rod 22 as shown in the dot and dash lines in Fig. 3, and then the finger 24 is removed from the opening 19 which is then ready to be closed.

The shuttle 13 lays the film 15 on the carrier when one is turning the carrier through the medium of the pulley 12 so that the film 15 is drawn out from the cartridge, and the shuttle 13 moves along the helical track 11b. When the film has been completely laid on the carrier it is necessary that the inner end of the film be cut off from the cartridge, since film cartridges are usually constructed with the inner end of the film secured to the core of the cartridge. For the cutting purpose there is a blade construction operable from

the outside of the device. This blade construction includes a razor blade 29 which is secured by several screws 30 upon the inner head end 31 of a flat bar 32 which extends out from a slot 33 in the end wall of the box bottom 10c. A head 34 is mounted on the extended end of the bar 32 by which it may be manipulated.

A track 35 is mounted upon the outer face of the side wall of the tank body 10b which is within the compartment 12 for the purpose of guiding the blade 29. The dot and dash lines 15' in Figs. 3 and 5 show the edge of the film 15. Since the blade 29 is located immediately adjacent the wall of the tank body 10 which is within the compartment 12 when the rod 32 is forced inwards, the blade 29 will cut the film free from the cartridge. This is clearly shown in Fig. 5 where the line 15' is shown crossing the blade 29, and obviously when the blade is moved it will cut the film.

Before the film is cut free from the cartridge it is necessary that a portion thereof be held down on the film carrier. For this reason a holding device which is operable from the outside of the tank is provided. This holding device includes a light-proof nipple 36 mounted through the wall of the cover 10a. A plunger 37 engages through the nipple 36. This plunger has a head 38 by which it may be moved. The inner end of the plunger 37 is provided with a socket 39. A spring or other resilient element 40 engages against the side of the socket and is mounted on the tank cover 10a for resiliently holding the plunger in its extended position. Normally, a clamp device is secured upon the socket 39. This clamp device comprises a pointed stud 41. The rear end of the stud has a threaded section 41a which is threadedly connected with the socket 39. A resilient finger 42 is fixedly mounted intermediate the ends of the stud 41. This resilient finger is adapted to extend over a portion of the film on the carrier 11. A rubber member 43 is attached upon the end of the finger and is adapted to engage a portion of the film on the carrier.

An arcuate track 44 is mounted on the end of the carrier 11 and is held spaced from the side wall of the carrier by several studs 45. This track 44 is of rubber or other friction material. The stud 41 is adapted to be forced in the space between the track 44 and the side wall of the carrier 11, and then fixedly maintains its position. The track 44 is arranged coaxial with the carrier 11 so that the holding device may be engaged thereon at different positions depending on the length of the film which has been removed from the cartridge. The track 44 has an auxiliary base track portion 44a secured on the side of the carrier 44 and cooperative with the spaced track portion 44 so that the stud 41 may be forced between these parts. Preferably, the stud 41 has flat sides and a pointed front so that it may be forced between the parts and frictionally securely maintain its position.

The opening 19 may be closed when desired. There is a shutter 46 guided at its ends by tracks 47 which are mounted upon the front wall of the tank cover 10a. The shutter 46 normally is disposed intimately against the inner face of the front wall of the tank cover 10a. Near the two ends of the shutter 46 there are projecting lugs 48 which have slots 49. Pins 50 engage into these slots and are mounted on the ends of arms 51 and 51' which extend rearwards and are mounted on rods 52 extending out through the end wall of the tank cover 10a. The shutter 46

is short on the left hand end relative to Fig. 4 to avoid striking the clamp device shown in Fig. 7. The arm 51' is bent to reach the lug 48 on the shutter 47.

5 Knobs 53 are secured on the outer ends of the rods 52. The shutter 46 normally maintains the raised position by friction with the tracks 47. The knobs 53 may be turned to indirectly move the arms 51 and so lower the shutter 46 as indicated by the dot and dash lines in Fig. 3. A strip of light-proof packing material 54 is secured along the bottom edge of the opening 18 against which the shutter 46 engages to produce a light-proof structure.

15 The tank 10 is provided with a capped opening 55 by which liquids may be poured into the tank. In the bottom of the tank there is a drain cock 56 by which they may be drawn off. Black felt or other light proof material 57 is mounted 20 on the side of the tank at the points where the rod 32 extends out, to guard against the entrance of light. The carrier 11 is shown provided with several inclined troughs 58 which will act to stir the liquid in the tank during the rotation of 25 the carrier.

The operation of the device is as follows:—

The box cover 10d is opened. A cartridge of film 15 is mounted on the carrier 11. The end of the film 15 from the cartridge is connected with 30 the hook 16a. The clamp device 42, 43, etc., is mounted upon the socket 39 as shown in Fig. 7. The rod 32 is extended as shown in Fig. 2. The finger 24 is engaged through the openings 19 against one side of the track 11b on the carrier 35 11. The cover 10d is then replaced. The wheel 18 is now manually turned.

When the wheel 18 turns it will turn the carrier 11 and the film 15 will be drawn out of the cartridge and laid helically on the carrier. The finger 24 will follow the helix of the track 11b and so the shuttle 13 will move along on the rod 22. When the film has been completely laid on the carrier, the carrier will be held against further turning as the inner end of the film is connected with the core of the cartridge 40.

45 The plunger 37 is then forced inwards against the holding action of the spring 40. The stud 41 will be forced in between the resilient tracks or rails 44 and 44a and the resilient head 43 will be forced against a portion of the film on the carrier as indicated in Fig. 4. The knob 38 is turned to disconnect the threaded connection between the socket 39 and the stud end 41a. The plunger 37 is then pulled backwards to its original 55 position leaving the film holding device on the carrier.

The rod 32 is then forced inwards so that the blade 29 cuts the end portion of the film completely from the cartridge. The screw 28 is then loosened and the radial arm 27 to turn the track 22 and so turn the shuttle 13, so that the finger 24 is removed from the opening 19 to the position shown by the dot and dash lines in Fig. 3. The knobs 53 are turned to move the shutter 46 down across the opening 19. This is merely a matter of precaution to further insure against light which may possibly enter the compartment 12 from reaching the film on the carrier, since it requires long periods of time to develop and fix supersensitive films.

70 The carrier is then rotated and the film developed, fixed, etc., by various liquids poured into and drained from the tank as more fully described in the co-pending application previously identified. When the film has been completely

developed and fixed the tank cover 10 is opened and the film is removed and is ready to be dried.

While the inventor has illustrated and described the invention with some degree of particularity, he realizes that in practice various alterations therein may be made. He therefore reserves the right and privilege of changing the form of the details of construction or otherwise altering the arrangement of the correlated parts without departing from the spirit or the scope of 10 the appended claims.

Having thus described the invention, what is claimed as new and desired to be secured by United States Letters Patent is:—

1. In combination with a developer tank for 15 strips of film having a light proof body housing a film carrier, a light proof holding box on said body and extending the length of said carrier and adapted to be opened, a shuttle for supporting a cartridge of film and movably mounted in said 20 box to move along the length of said carrier, a catch for holding the outer end of said film on said carrier, and means for operating said shuttle to move along said carrier and lay said film on said carrier. 25

2. In combination with a developer tank for strips of film having a light proof body housing a film carrier, a light proof holding box on said body adapted to be opened, a shuttle for a cartridge of film and mounted in said box, a catch for 30 holding the outer end of said film on said carrier, and means for operating said shuttle to lay said film on said carrier, said loading box extending the full length of the carrier and having a removable and replaceable cover. 35

3. In combination with a developer tank for strips of film having a light proof body housing a film carrier, a light proof holding box on said body adapted to be opened, a shuttle for a cartridge of film and mounted in said box, a catch 40 for holding the outer end of said film on said carrier, and means for operating said shuttle to lay said film on said carrier, comprising a controlling finger mounted upon the shuttle and engaging said film carrier. 45

4. In combination with a developer tank for strips of film having a light proof body housing a film carrier, a light proof holding box on said body adapted to be opened, a shuttle for a cartridge of film and mounted in said box, a catch 50 for holding the outer end of said film on said carrier, means for operating said shuttle to lay said film on said carrier, means operable from the exterior of said developer tank for securing an inner end portion of the film on said carrier, 55 and means for cutting off the end of the film from the cartridge.

5. In combination with a developer tank for strips of film having a light proof body housing a film carrier, a light proof holding box on said body adapted to be opened, a shuttle for a cartridge of film and mounted in said box, a catch for holding the outer end of said film on said carrier, means for operating said shuttle to lay said film on said carrier, means operable from the exterior of said developer tank for securing an inner end portion of the film on said carrier, and means for cutting off the end of the film from the cartridge, said film carrier having a helical track upon which the film is laid, and said means for 70 operating the shuttle including a finger engaging said track for moving the shuttle along the track during the laying operation.

6. In combination with a developer tank for strips of film having a light proof body hous- 75

- ing a film carrier, a light proof holding box on said body adapted to be opened, a shuttle for a cartridge of film and mounted in said box, a catch for holding the outer end of said film on said carrier, means for operating said shuttle to lay said film on said carrier, means operable from the exterior of said developer tank for securing an inner end portion of the film on said carrier, and means for cutting off the end of the film from the cartridge, said means for cutting off the end of the film comprising a stud extending into the tank and on its inner end supporting a blade adapted to cut the film when the rod is forced inwards.
7. In combination with a developer tank for strips of film having a light proof body housing a film carrier, a light proof holding box on said body adapted to be opened, a shuttle for a cartridge of film and mounted in said box, a catch for holding the outer end of said film on said carrier, means for operating said shuttle to lay said film on said carrier, means operable from the exterior of said developer tank for securing an inner end portion of the film on said carrier, and means for cutting off the end of the film from the cartridge, said means for securing the inner end of the film comprising a plunger extended to the exterior of the tank, a socket on the inner end of the plunger, a stud threadedly mounted upon said socket, a clamp for the film supported on said stud, a track mounted on said film carrier for receiving and holding said stud, and said plunger rotatable to disconnect the stud from the socket when the stud is mounted on said carrier.
8. In combination with a developer tank for strips of film having a light proof body housing a film carrier, a light proof holding box on said

body adapted to be opened, a shuttle for a cartridge of film and mounted in said box, a catch for holding the outer end of said film on said carrier, means for operating said shuttle to lay said film on said carrier, means operable from the exterior of said developer tank for securing an inner end portion of the film on said carrier, and means for cutting off the end of the film from the cartridge, the wall between said tank and said loading box being provided with an opening, said film being laid on the carrier through said opening, and a shutter for closing said opening.

9. In combination with a developer tank for strips of film having a light proof body housing a film carrier, a light proof holding box on said body adapted to be opened, a shuttle for a cartridge of film and mounted in said box, a catch for holding the outer end of said film on said carrier, means for operating said shuttle to lay said film on said carrier, means operable from the exterior of said developer tank for securing an inner end portion of the film on said carrier, and means for cutting off the end of the film from the cartridge, the wall between said tank and said loading box being provided with an opening, said film being laid on the carrier through said opening, and a shutter for closing said opening, comprising a shuttle element slidably supported to extend over the opening, pivotally mounted arms connected with said shutter and supported on rods extending through walls of said tank, and knobs upon the ends of the rods by which they may be turned to move the shutter.
